G. S. CHAPMAN,
MOLD FOR CONCRETING PILES.
APPLICATION FILED DEC. 29, 1913.

1,138,454.

Patented May 4, 1915.

UNITED STATES PATENT OFFICE.

GENERAL SHERMAN CHAPMAN, OF ST. PETERSBURG, FLORIDA.

MOLD FOR CONCRETING PILES.

1,138,454.

Specification of Letters Patent.

Patented May 4, 1915.

Application filed December 29, 1913. Serial No. 809,228.

To all whom it may concern:

Be it known that I, GENERAL SHERMAN CHAPMAN, a citizen of the United States, and a resident of St. Petersburg, in the county of Pinellas and State of Florida, have invented new and useful Improvements in Molds for Concreting Piles, of which the following is a full, clear, and exact description.

10 My invention relates to a means for applying a covering of concrete to piles after the latter have been driven.

An object of the invention is to provide a mold of the character indicated, so constructed and arranged that the mold may be applied and removed from the piles in water of any reasonable depth without the assistance of a diver.

The invention is distinguished by a split shell, and a locking key adapted to draw the edges of the shell together, and capable of being driven and removed by workmen standing on a dock above the piling to be treated.

25 The novel features entering into the practical embodiment of the invention serve to effectively and conveniently carry out the purpose of the invention, as hereinafter particularly explained.

30 Reference is to be had to the accompanying drawings forming a part of this specification, in which similar characters of reference indicate corresponding parts in all the views.

35 Figure 1 is a horizontal section of the edge portions of the shell and the tubular locking rod; Fig. 2 is a similar view showing a slightly different form; Fig. 3 is a similar view showing a further modification; Fig. 4 is a vertical section through the shell and locking rod, with the latter in position; Fig. 5 is a horizontal section of a shell with the locking rod removed, showing the pile with the concrete exterior molded thereon; and Fig. 6 is a fragmentary view 45 in vertical section representing a modification of the upper end of the locking rod.

The mold is adapted to form around the exterior of a pile A, a covering B of concrete of any desired thickness, and said mold comprises a shell 10, and a tubular locking rod 11 engages the opposed edge portions of the shell. The locking rod 11 is of rigid tubular material, having, in the 55 form shown in Fig. 4, a head 12 at the upper

end constituting a cross bar or T-head having a threaded socket to take onto mating threads, as at 13 on the rod, and there is formed in the rod at one side a longitudinal slot 14, which extends from the lower end to a point short of the head 12 so that the upper end of the rod is of unbroken continuity in cross section to resist expansion at the slot and to better receive the head 12 for the driving and pulling of the rod. In Fig. 6, the locking rod 11^a is formed in all respects the same as the rod 11, except that the head 12^a is in the form of an eye to receive a rope or hook, the lower end of the eye being in the form of a threaded socket 13^a.

Referring particularly to Fig. 1, the shell 10 at each edge is bent around a core 15, the material of the shell being out-turned in a lateral direction, as at 16, and then returned over the core 15, said core being spaced from the body of the shell and the returned portion of the shell being brought close to the web 16, as at 17, and then overlaid against the exterior of the shell, as at 18, rivets 19 being employed, or any other fastening method to unite the overlying terminal 18 to the body of the shell. The portions 16, 17, between the body of the shell and the core 15, thus constitute a web of double thickness on each edge portion of the shell so that the combined thicknesses of the webs will approximately fill the longitudinal slot 14 of the locking rod 11, while the cores 15 and the material of the shell bent around the same, form enlarged longitudinal beads at the outer edges of the said webs. The webs and beads, as will be observed, constitute mating members, the beads being disposed oppositely on respective edges so that they will be brought back to back and be received within the hollow interior of the rigid tubular rod 11 when the latter is applied. The construction makes it possible for workmen in a boat, to place the shell around a pile, with facility.

The rod 11 may be handled and controlled by workmen standing on the dock above the pile, and with the assistance of workmen below, the lower end of said rod is caused to engage the rear portions of a shell at the upper end of the latter. The rod may now be driven downwardly, and owing to its rigidity and the strength of the cored and returned edge portions, the said rod is driven downward and will grad-

ually draw the edge portions together to the bottom of the shell. The shell is of sufficiently greater diameter than the pile A to provide for whatever thickness of concrete 5 B is required. With the shell in position and closed by the locking rod, concrete is poured into the shell; when partially set, the rod is pulled upward through the dock, or equivalent platform provided above the 10 pile. In the event any concrete should find its way into the locking rod at the joint of the shell, it may find exit through transverse outlets 11^a formed in the back of the rod, said outlets being indicated in Fig. 4. 15 To facilitate the lifting of the shell 10, when the concrete has set, I provide means adapted to receive a manipulating hook (not shown), the hook consisting simply of an ordinary form of a handled elongated 20 shank having a hooked lower end. The hook is adapted to be engaged in loops or equivalent formations 20 provided on the shell. For convenience the loops 20 are disposed at different points around the shell 25 and at different elevations. These loops are shown as secured to metal strengthening bars or strips 20^a which extend vertically on the shell and are suitably secured as by rivets 20^b. The hook is first engaged in one 30 of the upper loops or hook-holds 20, and then after the shell has been partly raised, the hook is placed in one of the lower loops 20. In practice two hooks will engage the loops simultaneously.

35 The construction shown in Fig. 2 is similar to that in Fig. 1 in all respects, except that instead of disposing the extreme edges at both sides to overlie the exterior of the shell, one terminal 18 only is so laid on the 40 exterior. The material at the opposite edge portion is returned to the interior of the shell and is formed into a flap 21, which overlaps the opposite edge of the shell and thus covers the joint between the opposed 45 edge portions when the said edge portions are brought together.

In Fig. 3, the formation of the edge portions and cores is similar to that shown in Fig. 1, with the exception that in Fig. 1, 50 the cores 15 are plano-convex in cross section to present flat sides toward each other, whereas in Fig. 3, the cores 15^a are shown as round rods, and the portion 16^b of the material of the shell is bent round to conform to the rods, the elements 16, 17, 18 and 55 19 being the same as in Fig. 1. In all the constructions the form of the tubular locking rod is the same.

By the improved construction a concrete 60 covering can be applied to piles in any depth of water, say, even to thirty feet, without a diver manipulating the mold parts. The convenience of driving and pulling the locking rod from a dock or the 65 like above the piles not only facilitates the

placing and removing of the mold, but results in great economy of time.

Having thus described my invention, I claim as new, and desire to secure by Letters Patent:

1. A mold to apply a concrete casing around piles already driven, comprising a shell formed of tubular sheet metal split along one side only, and of unbroken continuity in cross section between the edges, 70 and a rigid locking rod in the form of a continuous tube to slidably engage the edge portions of the shell and secure the same, the said rod having a continuous longitudinal slot along a side thereof, and the said 75 edge portions of the shell presenting outwardly, mating, lateral webs adapted by their combined thickness to approximately fill the longitudinal slot of the rod and lie back to back when drawn together by the 80 rod, there being oppositely disposed longitudinal beads on the webs at their outer edges which are receivable in the interior of the rod, said rod being greater in length than the height of the shell and having 85 means at its upper end whereby the rod may be driven and withdrawn.

2. A mold to apply a concrete covering around piles already driven, comprising a split shell formed of bendable sheet metal, 90 and a rigid locking rod in the form of a continuous tube to slidably engage edge portions of the shell, said rod having a longitudinal slot along a side thereof extending from the lower end and terminating short of the upper end, there being a driving and pulling head on the upper end of the rod, the said 95 edge portions of the shell presenting outwardly disposed lateral webs, the web of each edge portion being returned on itself 100 so that each edge presents a web of double thickness, the combined webs approximately filling the longitudinal slot of the rod, there being oppositely disposed enlarged beads on the webs respectively within the hollow interior of the rod.

3. A mold to apply a concrete covering around piles already driven, comprising a split shell of tubular sheet metal and of unbroken continuity in cross section from one 115 edge to the other, and a locking rod for the opposite edge portions of the shell, said edge portions each having a core, the material of the shell extending outwardly and around said core and being returned on itself inwardly from said core, presenting beads at the cored portions and presenting lateral webs uniting the said cored portions to the said body of the shell, the locking rod being in the form of a longitudinal, continuous 120 tube, the length of the rod exceeding the height of the shell, and the upper end of the rod having a head whereby the rod may be driven and withdrawn, the rod furthermore 125 having a longitudinal slot below the head to 130

accommodate the webs of the respective edge portions of the shell.

4. A mold to apply a concrete covering around piles already driven, comprising a split shell each edge portion of which presents a member out-turned and then returned on itself, each edge thereby presenting a web of double thickness, the said webs having beads at the outer portions thereof and the two thicknesses of each web lying close together between the beads and the body of the shell; in combination with a tubular, longitudinally slotted locking rod to engage the said edge portions of the shell.
- 15 5. A mold to apply a concrete covering around piles already driven, comprising a shell, opposite edge portions of which are formed with beads, one of the edge portions being formed with an interior flap overlapping the opposite edge portion when the

shell is in the closed position; in combination with locking means to engage the said edge portions.

6. A mold to apply a concrete covering around piles already driven, comprising a 25 bendable sheet metal shell split longitudinally, the edges of the shell each presenting a member out-turned and then returned on itself, each edge thus presenting a lateral web of double thickness, the said webs having adjacent flat sides, and the side of each web opposite the flat side presenting a transversely rounding bead.

In testimony whereof I have signed my name to this specification in the presence of 35 two subscribing witnesses.

GENERAL SHERMAN CHAPMAN.
